Application June 13, 1935, Serial No. 26,375
In Switzerland June 21, 1934

5 Claims. (Cl. 58—67)

The present invention relates to a device for correcting instantaneously the angular position of one at least of the indicating members in a clock movement or timepiece, and particularly, 5 but not exclusively, of the minute-hand in a pocket watch, wristlet watch or in travelling clocks.

The device according to the invention enables an instantaneous correction to be made for example in the event of the minute-hand being slightly wrong, without recourse to the usual mechanism for setting the watch right. The angular position of the indicating member may be corrected at any moment, but this correction is 10 preferably effected at a fixed hour in accordance with a comparative horary apparatus marking the exact hour, or in accordance with an acoustic or optical time signal given at determined hours, for example by broadcast from an observatory, 15 by a siren, a semaphore or otherwise.

Furthermore the invention permits of an automatic corresponding correction of a time indicator related to the corrected one, e. g. the hour-hand and the minute-hand of a time piece.

In order that the invention may be clearly understood and readily carried into practice, reference will now be made to the accompanying drawing, in which an embodiment of the invention is illustrated by way of example, and in 20 which:—

Figure 1 is a part sectional view taken through the winding spindle of a watch movement with dial,

Figures 2 and 3 are part plan views of this 25 movement, the dial being broken away in order to show some of the parts disposed beneath the dial.

In the drawing may be seen the frame 5 of the 30 movement, the dial 6, the minute-hand 7, the hour-hand 8, the winding spindle 9, the pinion 10 and the centre gear 11, and also the dial-work or train comprising a toothed wheel 12 having twelve cogs, the barrel wheel 13 integrally incorporating an outer sleeve 13a, the hour gear 14 and its pinion 15. None of these parts needs further explanation, because they occur in any keyless 35 watch movement of modern construction. The inner toothed wheel 12 has a tubular boss or 40 central axial sleeve extension 12a and is fitted to engage frictionally with the shaft or arbor 16 of the pinion 10 and is thus entrained by frictional engagement by the said shaft 16. The said tubular boss 12a carries the minute-hand 7.

On the plate of the frame 5 there is fixed at 45

18 a hammer arm 17 which is elastic or flexible at 17'. This hammer arm is provided with a hammer or head 19 which, when the hammer is at rest, supports itself against the inner extremity of the winding spindle 9. The latter is mounted 5 with a supplementary axial play which enables it to be pushed beyond its winding-up position in such a manner that the hammer arm 17 may be actuated by means of the winding spindle to cause a wedge-like nose 19' of the head 19 of the hammer to act upon the cogs of the wheel 12. The nose 19' possesses two faces symmetrical with respect to the axis passing through the winding spindle and the centre of rotation of the wheel 12. The wheel 12 possesses twelve cogs, and the arrangement is such that two adjacent cogs will 10 be located opposite to the nose 19', symmetrically on each side of the said axis, each time the minute-hand passes over a stroke marking five 15 minutes on the minutes graduation of the dial 6 20. (Fig. 3). As a consequence of this arrangement the owner of the watch is able instantly to correct the position of the minute hand 7 and to rectify an error thereof of about two and a half 25 minutes too much or too less (fast or slow) at the maximum, by pressing upon the winding knob (which is capable of an axial movement additional to its normal capability for movement) whilst observing the minute hand of an apparatus marking the exact time or an optical 30 horary system, or at the moment he observes an horary acoustic signal given for example by a broadcasting station. Actually, if the minute hand is, for instance, two minutes fast as shown 35 in Figure 2, it immediately effects a backward movement through an angle corresponding to two divisions of the minutes graduation of the dial (Figure 3), the wheel 12 being shifted back by a like angle by the hammer 17, the nose 19' of 40 which engages in the cogs of said wheel the moment the winding spindle actuates the hammer. The position of the hour-hand is simultaneously 45 rectified in a ratio of 12:1, since the wheel 12 is in geared connection with the barrel wheel 13 by means of the gear 14 and the pinion 15 of the hour mechanism. As soon as the owner ceases to 50 press upon the knob or on the winding spindle, the latter is returned to its original position under the action of the hammer 17, which as explained above is resiliently flexible.

The operations are the same when the hand 7 is late, with the difference that the minute-hand is given a corrective catch-up movement, that is to say, a movement in its positive direction of rotation. 55

The essential point is to determine for each form of embodiment of the invention the speed ratios of the gears and the relative position of the hammer and the mover controlled by this hammer.

The term "hammer" is to be interpreted in its widest sense, for the hammer may be formed by any member controlled directly or indirectly and acting radially, by means of a nose or tooth, 10 on the cogs of the mover whose angular position is to be corrected.

What I claim is:—

1. In a timepiece having a winding spindle, means for correcting the angular position of a 15 time-indicator, such means comprising a movable arm one end of which is connected to a stationary part of said timepiece, and the other and free end of which is movable from the exterior of the timepiece, said arm having a nose 20 at its free end, and a part associated with said indicator and adapted to co-operate with said nose to produce an angular adjustment of the indicator on the said nose being moved relative to the timepiece, and said arm being operable 25 from the winding spindle of the timepiece, which spindle is axially slidable.

2. A timepiece comprising a central arbor, a toothed wheel in frictional engagement with said arbor, an indicating hand directly driven by said 30 toothed wheel, a further indicating hand, gearing through which said further indicating hand is driven from said toothed wheel, a hammer anchored at one end to the frame of said timepiece and having at its free end a nose, a spindle 35 depressible from the exterior of the timepiece, said spindle, in being moved to its depressed position being adapted to force the nose of said hammer into engagement between two adjacent teeth of said toothed wheel and adapted 40 thereby to shift said wheel so that the said two adjacent teeth assume positions in which they are symmetrical with respect to the line of motion of said hammer nose.

3. A timepiece comprising a central arbor, an 45 inner toothed wheel having a central axial sleeve extension, said inner toothed wheel and extension being in frictional engagement with said arbor, a minute indicating hand mounted directly upon said sleeve extension and adapted to be 50 driven therewith, an outer sleeve, a toothed bar-

rel wheel and an hour indicating hand, said toothed barrel wheel being integral with said outer sleeve and said hour indicating hand being mounted directly upon said outer sleeve and adapted to be driven therewith, a gear train 5 adapted to transmit the movement of rotation of said inner toothed wheel at a reduced rate to said toothed barrel wheel, a hammer anchored at one end to the frame of said timepiece and having at its free end a nose, a spindle depressible from the exterior of the timepiece, said spindle being adapted in its depressed position to force the nose of said hammer into engagement between two adjacent teeth of said inner toothed wheel and adapted thereby to rotate 10 said wheel so that the said two adjacent teeth assume positions in which they are symmetrical with respect to the line of motion of said nose.

4. A keyless timepiece including a frame, two time indicating members, a toothed wheel rigidly associated with one of said indicating members, a driven arbor with which said toothed wheel is frictionally engaged, reduction gearing by which the said toothed wheel and the indicating member rigidly associated therewith is 25 geared to the other indicating member, a manually operable winding spindle which is capable of axial movement additional to its normal movements, a hammer, a spring hammer arm at one end of which said hammer is carried and the 30 other end of which is fixed to said frame, said hammer normally being engaged by the inner end of said winding spindle and having a nose of wedge form which is adapted to co-operate with said toothed wheel, for the purpose specified. 35

5. A keyless timepiece including a frame, two time indicating members geared together, a toothed wheel frictionally associated with the driving means for one of the time indicating members and fixed to the latter, a manually operable winding spindle capable of endwise movement, a hammer resiliently retained in engagement with the inner part of said winding spindle and having a nose adapted to engage between any two adjacent teeth of said toothed wheel (when 45 the hammer is depressed by said winding spindle) thereby to shift angularly said toothed wheel and the time indicating member associated therewith.
